Term of patent 3½ years

(Cl. D33—6)

FIG. 4

FIG. 1

Fig. 1 is a perspective view of a chest embodying my new design, the perpendicular lines on the top drawer and the two lower drawers being representative of grooves;

Fig. 2 is a front elevational view of the chest of Fig. 1;

Fig. 3 is a plan view of the chest of Fig. 1; and

Fig. 4 is a side elevational view of the chest of Fig. 1.

The dominant features of the design reside in the portions shown in full lines.

I claim:

The ornamental design for a chest, substantially as shown and described.
